UNITED STATES PATENT OFFICE.

ERNEST OLDENBUSCH, OF BROOKLYN, NEW YORK.

PERPETUAL CALENDAR.

Application filed February 26, 1927. Serial No. 171,229.

This invention relates to a perpetual calendar designed to be placed on the tops of desks and the like to indicate the months and days of successive years.

5 The principal object of the present invention is to provide a perpetual calendar embodying improvements in construction making it comparatively inexpensive, readily operable to effect a change from one calendar 10 month to another as the occasion arises, and one which is ornamental in appearance.

The nature of the invention and its distinguishing features and advantages will appear when the following specification is read 15 in connection with the accompanying drawing, in which—

Figure 1 is a perspective view of a calendar embodying the features of the present invention.

20 Fig. 2 is a sectional view taken on the line 2—2 of Fig. 1.

Fig. 3 is a sectional view taken on the line 3—3 of Fig. 1.

Fig. 4 is a collective view of the month 25 indicating disk, the plate which carries the disk, and the tubular members around which an endless strip bearing numbers denoting days is passed.

Fig. 5 is a rear view illustrating more 30 clearly how the month indicating disk is connected with the plate.

The device includes a casing made up of 35 two parts, a part 10 and a part 11. The part 10 is stamped, bent and formed from a single piece of metal to provide a front portion 12, side portions 13, top portion or flange 14, lugs 15, and the front portion 12 having a small sight opening 16, a comparatively large sight opening 17, and an indenture 18. 40 The front portion 12 is also cut out as at 19 for a reason to appear. The front portion 12 being cut out as at 19 provides members 20 which with the bottom edges of the side portions 13 provide means upon which 45 the device in its entirety stands, with the front portion 12 inclined. The part 11 is in the form of an open sided box, which is stamped and formed from a single piece of metal. The said part includes a back 21

50 and wall portions 22. The lower wall portion 22 is cut out as at 23. The part 11 fits between the top of the flange 14, lugs 15, and the side portions 23 and is releasably held in place by indentations 24 respectively in the side portions 13. These portions are slightly flexible in order to allow the part 11 to

be put in place. A transparent panel of celluloid 25 is arranged within the casing adjacent the sight opening 17. The panel 25 has a slot 26 therein. Stamped, bent and formed from a single piece of metal, there is provided a plate 27 having top and bottom flanges 28 and 29 respectively and rearwardly directed portions 30, 30 and 31 at each end of the plate, a central arbor 32, an opening 33 near the top, and a slot 34 at the bottom of the plate which opens into the bottom flange 29. A disk 35 is provided, the circumferential edge of which is provided with twelve projections 36, and one face of the disk has printed thereon matter denoting the months of a calendar year, in abbreviation. These abbreviations 37 are arranged circumferentially with respect to the projections 36. The disk 35 is associated 70 with the plate 27 by virtue of the arbor 32 which extends through the hole located centrally of the disk, and the tension member 38 which is held in place by small clips 39 struck up from the arbor 32. These clips engage 75 notches in the opposite sides of the tension member 38. The disk 35 may be rotated with respect to the plate 27 and will be under the influence of the tension member 38 which releasably retains the disk in different 80 positions to which it is moved. It will be seen that the abbreviations 37 appear at the opening 33 in the plate, and that the projections 36 are adapted to pass through the slot 34. The plate 27 and its disk 35 are 85 arranged in the casing, which brings the opening 33 in the plate in registration with the small opening 16 in the front portion 12 of the casing. The projections 36 on the disk 35 are adapted to pass through the cut-out 23 in the bottom flange 29. It will now be understood that each of the projections 36 may be thumbed to effect the rotation of the disk 35. The indenture 18 is provided with an abutment 40 which is encountered 90 by the thumb in the movement of the disk which will insure registration of one of the abbreviations 37 with the aligned openings 16 and 33.

In order to denote the days of the calendar 105 year, there is provided a strip of paper or the like 41. One face of the strip 41 has printed thereon a series of numbers 42 which denote the days, and are supplemented by the names of the days of the week which 110 appear in abbreviated form on the front portion 12, as at 43. The strip 41 is passed

around the plate 27 and tubular members 44 rotatably retained in place by the portions 30, 30 disposed respectively at the upper and lower ends of the related tubular member, and portion 31. The opposite ends of the strip 40 are pasted together as at 45. The strip 41 and the portions 31 of the plate maintain the proper spaced relationship of the tubular members 44 which function as 10 rollers. The strip 41 is thus arranged for easy movement so as to bring any desired combination of numbers 42 adjacent the sight opening 17 to formulate a calendar month which will be indicated by one of the 15 abbreviations 37. Movement of the strip 41 is effected by a lug 46 secured to the strip in any suitable manner. The said lug 46 extends through the slot 26 in the transparent panel 25 so that it may be thumbed to effect 20 the movement of the strip.

I claim:

1. In a perpetual calendar, a casing having a sight opening, a transparent panel having a slot arranged adjacent the sight opening, a plate arranged within the casing adjacent the transparent panel, a separate roller at each end of the plate, an endless strip passed around the plate and rollers,

each of said rollers being kept in place for rotatory movement by portions of the plate 30 and the strip, said strip having numbers on one face thereof denoting days of the calendar months, and a lug on said strip which extends through said slot for effecting the 35 adjustment of said strip.

2. In a device of the class described, a casing having a sight opening, a separate transparent panel fitting within the casing, disposed adjacent the sight opening, and having a slot therein extending longitudinally of the panel, a separate plate fitting within the casing, an endless indicia bearing strip, separate rollers, there being one roller at each end of said plate, each roller being kept in place for rotatory movement by angularly disposed portions on the related end of the plate and said endless strip to allow movement of the strip which encircles the rollers and plate, a portion of the endless strip being disposed adjacent the sight opening in the casing and visible through said transparent panel, and a lug on the endless strip extending outwardly through said slot for moving the endless strip. 45

ERNEST OLDENBUSCH.
